SHOE OUTSOLE SEWING MACHINES

Joseph R. Ioannilli, Beverly, Mass., assignor to United Shoe Machinery Corporation, Boston, Mass., a corporation of New Jersey

Filed Feb. 20, 1961, Ser. No. 90,326

21 Claims. (Cl. 112—32)

This invention relates generally to improvements in loop lock stitch shoe outsole sewing machines and more particularly to combinations of thread handling and work feeding devices for achieving more uniform stitches than has heretofore been possible especially at the higher operating speeds in such machines.

In many respects a well formed loop lock stitch seam is preferable to the conventional shuttle lock stitch usually employed to connect the outsole of the shoe to the welt. The present invention is directed to machines for forming seams in stubborn or resistant material referred to generally in the specification and the claims as "leather" but this term will be understood to include not only natural leather but rubber, plastic, composition and similar materials for shoe soles. Since the formation of a loop lock stitch requires the passage through the work of only a fraction of the needle thread involved in the formation of a conventional lock stitch, there is consequently less wear upon the thread and the speed of the sewing operation can therefore be accordingly increased while at the same time preserving the needle thread in better condition in the completed stitches. It will also be appreciated that in a well formed loop lock stitch seam there is a greater difference between maximum and minimum cross sections of thread in each stitch hole and the resultant seam is therefore characterized by greater holding power particularly after the locking thread has been cut by wear.

Inherent advantages also abound in favor of loop lock stitch sewing over conventional lock stitch sewing in terms of machine concepts. For example, since less thread is moved through the work during the formation of each stitch the machine instrumentalities for expanding needle loops and for retracting needle thread may be actuated more simply and reliably over the shorter necessary distances. Another example of a favorable machine aspect is the elimination of the shuttle which is costly to manufacture, install and replace. Instead of a shuttle, a loop lock sewing machine includes a combination of inexpensive, individually simple thread manipulating instrumentalities each of which may be manufactured and replaced with ease and at low cost.

In spite of the inherent advantages both from the point of view of the product and of the machine it has heretofore been impossible to provide a loop lock stitch shoe outsole sewing machine capable of inserting a seam of such quality as to be entirely acceptable by the shoe industry to replace conventional shuttle machines. Prior loop lock stitch machines are not generally commercially acceptable largely because these machines do not produce seams which, from external inspection, exactly duplicate conventional shuttle lock stitch seams. Prior loop lock stitch machines do not simulate conventional seams because of two different forms of defect in the seam. The first of these is the frequent appearance of locking loop bights on the tread surface of the outsole whenever the sewing conditions are rendered difficult either by the sewing speed or by abrupt conditions of curvature. Exposed bights may also stem from the nature of the work piece itself when, because of thickness limitations, extreme accuracy is necessary in the formation and setting of the stitches or the material interferes with the free movement of the thread. Another defect which hampers the ac-

2

ceptance of prior loop lock stitch shoe sewing machines is the frequency with which stitches are missed completely by the failure of the locking thread loop to prevent the needle thread loop from being pulled completely through the work.

It is accordingly a general object of the present invention to improve the reliability and uniformity of stitch forming operations carried on particularly at high speed in loop lock stitch shoe sewing machines.

10 It is another object to improve the accuracy in the depth to which loop lock stitches are set in work pieces.

Still another object is to provide stitch forming instrumentalities capable of operation at high speed to form seams having the superior inherent qualities of loop lock stitches while at the same time retaining the external appearance of the more conventional and heretofore acceptable shuttle lock stitch seams.

15 A further object is to gain a more uniform arrangement of thread in the individual stitch holes of each seam by more exact control of feeding movement imparted to the work.

20 Yet another object is to provide instrumentalities for handling the needle thread in loop lock stitch sewing machines so that deposits of lubricating and adhesive substances may be carried by the needle thread to the work without any possibility that these substances will be stripped from the thread by the handling instrumentalities.

25 A more particular object of the invention is to provide a loop lock stitch outsole stitcher in which the work piece is continuously clamped during the formation and setting of each stitch.

30 Another particular object is to provide a loop lock stitch shoe sewing machine in which the setting of the stitch is accomplished with accuracy by imposing the full stitch setting tension upon a short length of needle thread subject to a minimum of erratic elongation.

35 Yet another specific object of the present invention is to improve the accuracy of needle thread measurement to contribute further to uniformity of stitch setting depth.

40 The foregoing objects are attained in a loop lock stitch outsole stitcher having a curved hook needle and some stitch forming devices similar to those disclosed in United States Letters Patent No. 2,877,725, issued March 17, 1959, in my name and in applications for United States Letters Patent Serial No. 750,392, filed July 23, 1959 and No. 831,735, filed August 5, 1959 in my name and that of Clyde A. Knott respectively. As in the machine of the Knott application, the needle cooperates with a curved awl entering the perforations previously

45 formed by the awl and retracting from the work piece carrying loops of needle thread. The needle, awl and a work feeding clamp comprising a work support and a presser foot cooperate in the present machine for continuously advancing the work throughout the full sewing cycle but according to a feature of the invention in a novel time sequence to achieve more uniform stitches while maintaining more accurate control over the work piece. The work feeding clamp engages the work piece early in the stitch forming cycle and maintains its control uninterrupted during the thread measuring function, thereby improving the accuracy of needle thread measurement.

50 In accordance with another feature of the present invention the illustrative machine includes a stitch setting gripper which cooperates with a takeup similar to that of the Knott machine for setting each stitch after the needle loop has first been contracted by the takeup. The result of this feature is that the full stitch setting tension is applied to but a short length of thread between the work piece and the gripper while a much lower tension is exerted upon a substantial length of needle thread during that part of the stitch forming cycle when, in contracting

the needle loop, the thread moves with relative freedom through the work piece.

Yet another feature of the invention is embodied in actuating connections for the stitch setting gripper, arranged for precise adjustment of the stitch setting motion to be imparted to the thread in accordance with the characteristics of the work upon which the sewing operation is being performed. An associated feature relates to a single set of actuating connections for opening and closing the gripper and for providing the stitch setting motion.

Still another feature of the present invention relates to an actuating cam included in the machine for operating the stitch setting gripper to perform not only the stitch setting operation but also an important and novel secondary function. The gripper actuating cam in addition to having a major lobe for the stitch setting function is also provided with a minor lobe which closes the gripper upon the needle thread during that part of the sewing cycle when the needle is being threaded. Along its entire path, the needle thread, after emerging from a wax pot of generally conventional design in the present machine, is entirely free of devices which control its movement by static friction. In the present machine, therefore, it is possible to apply to the needle thread thick coatings of substances which are carried to the work first to lubricate the thread and provide for its free passage and thereafter to assist in bonding the thread to the work piece for improving the security of the seam. The movement of heavy coatings by the needle thread is possible without loss of control over the thread because the gripper maintains the needle thread taut for reliable placement in the barb of the needle without causing removal of the coating by moving the thread through a device having a stripping action.

According to still another feature of the invention the stitch setting gripper includes a secondary actuating means effective for opening the gripper upon stopping the machine at the end of a seam to permit unhampered withdrawal of the work piece from the machine. During the continuation of a seam the gripper is actuated twice during each sewing cycle, once to grip the thread as the needle is being threaded and secondly to grip the thread and impart to it a stitch setting motion at the end of each sewing cycle. These two regular motions of the gripper are cam actuated and entirely repetitive. After the final stitch of a seam has been set, however, the gripper, which would otherwise be closed, is opened to permit withdrawal of the work piece by an auxiliary action independent of the actuating cam.

Additional features of the invention cooperate with the auxiliary opening of the stitch setting gripper to expedite the removal of the work piece from the machine at the end of the seam. Included among the additional features is an auxiliary thread measuring device which draws through the wax pot a quantity of needle thread in preparation for the stoppage of the machine and upon stopping the machine releases the excess thread so that the leading end may more easily be held in position for the start of a new seam.

In the achievement of the foregoing objects, the features of the present invention are included in a loop lock stitch shoe outsole sewing machine to be described with reference to the accompanying drawings in which,

FIG. 1 is a general view in front elevation of a shoe sewing machine including the features of the present invention;

FIG. 2 is a fragmentary view on an enlarged scale and in front elevation of the machine depicted in FIG. 1;

FIG. 3 is a view in right side elevation of the machine of FIGS. 1 and 2;

FIG. 4 is a view in cross section and on an enlarged scale showing a work piece with a single stitch hole in which a conventional shuttle lock stitch is positioned with the lock set deep in the work;

FIG. 5 is a view similar to FIG. 4 but showing the thread lock set shallow in the work piece;

FIG. 6 is a view similar to FIGS. 4 and 5 but showing the thread lock set at a medium depth in the work piece;

FIG. 7 is a view taken along the line VII—VII of FIG. 6 showing the maximum thread cross section;

FIG. 8 is a view of the minimum thread cross section in a stitch hole taken along the line VIII—VIII of FIG. 6;

FIG. 9 is a view in cross section and on an enlarged scale showing a single stitch hole in which the thread lock of a loop lock stitch is set deeply in the work piece;

FIG. 10 is a view similar to FIG. 9 but showing the thread lock set at a shallow depth in the work;

FIG. 11 is a view similar to FIGS. 9 and 10 but showing the thread lock of a defectively formed loop lock stitch set at a medium depth in the work;

FIG. 12 is a view similar to FIGS. 9 to 11 and showing a correctly formed loop lock stitch set at a medium depth in the work;

FIG. 13 is a view of the maximum thread cross section taken along the line XIII—XIII of FIG. 12;

FIG. 14 is a view of an intermediate thread cross section taken along the line XIV—XIV of FIG. 12;

FIG. 15 is a view of the minimum thread cross section taken along the line XV—XV of FIG. 12;

FIG. 16 is a view in rear elevation of the machine of FIGS. 1 to 3 showing more particularly switches and other control connections actuated in stopping the machine;

FIG. 17 is a detailed view in right side elevation of a treadle connected device actuated in starting and stopping the machine;

FIG. 18 is a view looking from the right side of the machine illustrating devices which are actuated in stopping the machine, the parts of the devices being shown in the relative positions occupied just before the machine comes to rest;

FIG. 19 is a view in side elevation, partly in cross section, showing a thread severing control switch effective at the end of the seam;

FIG. 20 is a view in left side elevation and partly in section showing a carriage on which the needle and awl are mounted and also the actuating connections for the needle and awl;

FIG. 21 is a plan view showing the needle and awl carriage, a similar carriage for a work clamp and connections for imparting to these two carriages work feeding motions;

FIG. 22 is a detailed view taken in the direction of the arrow 22 in FIG. 20 showing actuating mechanisms for the needle and clamp carriages;

FIG. 23 is a fragmentary view in front elevation showing stitch forming and work feeding instrumentalities about the sewing point of the machine;

FIG. 24 is a view in left side elevation depicting a stitch setting gripper according to a feature of the invention together with its actuating mechanisms;

FIG. 25 is a view also in left side elevation illustrating in addition to the stitch setting gripper of FIG. 24 a thread controlling takeup, thread locks and a thread measuring device;

FIG. 26 is a schematic diagram showing connections of electrically actuated devices in the machine;

FIG. 27 is a schematic illustration in perspective depicting the arrangement of thread controlling instrumentalities of the machine;

FIG. 28 is a detail view of the parts of the stitch setting gripper shown in exploded relationship;

FIG. 29 is a detail view in left side elevation showing a thread measuring device, thread locks and their actuating mechanisms incorporated in the present machine;

FIG. 30 is a schematic view in cross section showing a

work piece and including loop lock stitches being formed under optimum work feeding conditions;

FIG. 31 is a view similar to FIG. 30 but showing a later stage in the formation of a loop lock stitch under optimum work feeding conditions;

FIG. 32 is a plan view of loop lock stitches being formed under the same conditions as depicted in FIGS. 30 and 31;

FIG. 33 is a view similar to FIG. 30 but showing the formation of loop lock stitches under work feeding conditions which cause rearward deflection of the needle along the line of the seam;

FIG. 34 is a view similar to FIG. 31 but showing the action and relative position of the needle and the work as the needle emerges from the work after having been rearwardly deflected by resistance to work feeding motion;

FIG. 35 is a plan view similar to FIG. 32 but depicting the formation of loop lock stitches under conditions of rearward needle deflection;

FIG. 36 is a schematic view similar to FIGS. 30 and 33 but showing the formation of loop lock stitches while the needle is deflected forwardly along the line of the seam;

FIG. 37 is a view similar to FIG. 34 illustrating the action of the needle upon emerging from the work after having been deflected forwardly along the seam;

FIG. 38 is a plan view similar to FIG. 35 but illustrating the formation of loop lock stitches, under the conditions of forward needle deflection; and

FIG. 39 is a time chart of the present machine.

The present machine is equipped with a curved hook needle 2 (FIGS. 20, 23 and 25), a curved awl 4, a thread hook 6, a work support 8, a presser foot 10, and loop lock stitch forming and work feeding devices generally similar to those disclosed in the Knott application. The work support and presser foot, as in the Knott machine, comprise a clamp which cooperates with the needle and awl for imparting a continuous feeding movement to the work. In the present machine, however, a novel timing sequence in the entry of the needle and awl into the work piece and the gripping and releasing movements of the clamp has resulted not only in improved uniformity in stitch length but also in a high consistency in the placement of thread in successive stitch holes as will later be explained.

The stitch forming and work feeding devices of the present machine are actuated by cams on a main and a secondary sewing shaft 12 and 14 respectively (see FIG. 3), the two shafts being geared together at a 1-1 ratio and journaled in a machine frame 16 for rotation in opposite directions. Movement is imparted to the work feeding clamp 8, 10 by a grooved cam 18 mounted on the main cam shaft 12 as shown particularly in FIGS. 21 and 22. As in the Knott machine the work feeding clamp is supported upon a carrier 20 pivoted on a rearwardly inclined shaft 22 fixedly supported in the machine frame 16. The rearward end of the carrier 20 is connected through an adjustable toggle arrangement indicated generally at 24 and more fully described in the Knott application with a composite bell crank including a forwardly extending arm 26 secured to a vertical shaft 28. At its forward end the arm 26 carries a follower roll 30 engaging the groove of the cam 18.

The needle and awl as in the Knott machine are mounted for rotation about a common stud or pin 32 supported at the forward end of a carrier 34 also pivoted upon the inclined shaft 22. For imparting a work feeding movement to the carrier 34 it is connected by a toggle arrangement indicated generally at 36 to a bell crank 38 which also carries a follower roll 40 in engagement with the groove in the cam 18 at a position 180° from the follower roll 30. The toggles 24 and 36 comprise respectively similar links and are provided with adjustably fixed coaxial pivots in a slide 42 which may be positioned for

simultaneously varying the extent of movement of the two carriers 20 and 34 in approximately the same manner as in the Knott machine.

The mounting of the needle and awl on the stud 32 is also similar to that disclosed in the Knott application, there being in the present machine an adjusting and locking arrangement for relatively positioning a needle segment 44 and an awl segment 46 so as to aline the needle and awl in a common vertical plane. The stud 32 which is adjustably fixed in the forward end of the carrier 34 also provides an axis for a conventional needle guide 48 and the arrangement for alining the needle and awl on the stud is similar to that disclosed in United States Letters Patent No. 2,271,611 granted February 3, 1942 upon an application of Fred Ashworth et al.

As may be seen particularly in FIG. 20, the needle and awl are actuated for their work penetrating motions by mechanisms similar to those of the Knott machine. The actuating mechanisms for the needle and awl include 20 two pairs of conjugate cams on the main cam shaft 12 and connections to the needle and awl segments. Between the conjugate cams for actuating the needle, and the segment 44 on which the needle is fixedly mounted is a lever 52 and a similar lever 54 is interposed between the awl 25 actuating cams and the segment 46, both the levers 52 and 54 being pivoted upon a fulcrum shaft 56 fixedly supported in the frame of the machine. Connecting the lever 52 to the segment 44 is a short link 58 and a similar link 60 is included between the forward end of the lever 25 54 and the awl segment 46. At its rearward end the needle lever 52 carries a follower roll 62 engaging the periphery of a cam 64, one of the pair of conjugate cams for actuating the needle. A secondary follower roll 66 is mounted on an arm 68 pivoted on the shaft 56 and 30 35 yieldingly coupled with the lever 52. The follower roll 66 engages the periphery of a cam 70 and the yielding coupling between the arm 68 and the lever 52 allows the distance between the rolls 62 and 66 to be varied slightly to compensate for minor variations in the theoretically correct cam profiles. A similar arrangement is 40 provided for oscillating the lever 54 to impart a work penetrating motion to the awl by conjugate cams 72 and 74 also mounted with the cams 64 and 70 on the main shaft 12. The periphery of the cam 72 is engaged by 45 a follower roll 76 rotatable on the rearward end of the lever 54 and a secondary roll 78 on an arm 80 is in engagement with the periphery of the cam 74. The arm 80 is pivoted on the shaft 56 and yieldingly coupled to the lever 54 to take care of minor irregularities in cam 50 contour.

From the foregoing brief summary of the mechanisms for imparting work feeding motions to the carriers 20 and 34 and work penetrating movements to the needle and awl it will be appreciated that by retaining similarities in general construction the present machine also retains those advantages more fully described in the Knott application. Among these advantages are two principal ones stemming from the rearward inclination of the common pivot upon which the carriers 20 and 34 are fulcrumed and the orientation with respect to the point of needle and awl penetration of the area of effective pressure applied by the work feeding clamp. The retention in the present machine of the rearward inclination of the pivot for the carriers results in a rising and falling motion of the work support during feed thereby producing a crease opening action during backfeed and a desirable squeezing action during work advance. The movement of the area of maximum pressure imposed by the presser foot bearing on one side only of the needle plane tends to draw the work piece slightly into the machine during each sewing cycle thereby facilitating the guidance of the work.

While the present construction retains the major advantages of the Knott machine as already pointed out, the novel timing of the present machine results in the seam having much greater uniformity both as to the

length of stitches and as to depth of thread lock setting than has heretofore been possible in loop lock stitch shoe outsole sewing machines. Later in this specification the improved timing will be described in detail as a part of the presentation of the complete sewing cycle with reference to the time chart. For the moment it will be pointed out that the improved sewing cycle of the present machine employs the awl for advancing the work piece while the work support and the presser foot are being backfed and the time allotments to the awl and work feeding clamp are such that during the entire portion of the sewing cycle, beginning with the needle withdrawing from the work piece, carrying a loop of thread until the stitch has been completely formed and set in the body of the work piece, the work feeding clamp maintains absolute and exclusive control over the work piece. The control of the work piece is assumed by the work feeding clamp before the needle reaches its point of deepest penetration in the work so that both the stitch length and stitch formation are accordingly improved.

In some respects the operation of the stitch forming devices of the present machine including, in addition to those already mentioned, a looper 86 and a locking thread carrying finger 88 (FIGS. 23 and 27), is generally similar to that of prior loop lock stitch sewing machines. In the formation of a stitch, the needle penetrates the work through a perforation priorly formed by the awl and the loop of thread is laid in the barb of the needle by an orbital movement of the looper 86. Before being placed in the barb of the needle, the needle thread indicated at 90 is wrapped about the thread hook 6 which then moves rearwardly to take up a quantity of needle thread between the work piece and the barb of the needle to be thereafter given up as the needle is withdrawn from the work. As the needle approaches its most elevated position above the work, that shown in FIGS. 25 and 27, the needle loop is engaged by a loop spreader 92 and opened for entry into the spread loop of the locking thread finger 88.

A loop of locking thread indicated at 94 is formed by the cooperation of the thread finger 88 with a locking loop detaining finger 96 which descends to engage the work in a position to trap the locking thread which is formed into a loop as the finger 88 is withdrawn from the needle loop. Thereafter the needle dips toward the work and a castoff 98 (FIG. 23) disengages the thread from the barb of the needle as the loop spreader 92 moves rearwardly to free the needle loop so that it may be contracted by the action of a takeup 100 (FIG. 25) which applies a pull to the needle thread to retrieve the thread from the previously expanded needle loop. The locking loop detaining finger 96 remains in contact with the work piece until the needle loop is fully contracted about the locking loop, the locking thread carrying finger 88 having returned to the left of the needle plane as the needle loop is being contracted. At a point when the contraction of the needle loop has progressed sufficiently that the locking loop is gripped firmly upon the upper surface of the work, the thread retrieving function of the takeup 100 in the present machine is completed and any subsequent movement of the needle thread for setting the thread lock in its final position within the work is accomplished by a gripper indicated generally at 102. As the needle thread moving function is transferred from the takeup 100 to the gripper 102 the finger 96 is raised out of engagement with the work piece to permit the escape of the locking loop which is thereafter free to be carried into the work by the needle thread under the tension applied by the stitch setting gripper.

The importance and value of the gripper 102 among the thread handling instrumentalities of the present loop lock stitch shoe outsole sewing machine will be appreciated from a comparative appraisal of the problem presented in setting loop lock stitches as opposed to conventional lock stitches, particularly with reference to

FIGS. 4 to 15 inclusive. A single stitch hole in a two-ply work piece comprising an outsole 110 and a welt 112 is shown in FIG. 4. In the stitch hole is arranged the thread consisting of a needle thread 114 and the locking thread 116, engaged to form a thread lock. In FIG. 4 the thread lock 114, 116 is shown set in the work at a maximum depth considered suitable for outsole attaching. If the depth to which the thread lock is set is increased even slightly beyond the showing of FIG. 4 there is the danger that an unnoticed deviation in the normal operation of the machine, for example, an error in thread measurement, might cause the thread lock to be set in the welt. Such a stitch would have only such holding power as was derived from adhesion of the thread in the stitch hole after the locking thread was cut during normal wear. FIG. 5 illustrates a single stitch hole in an outsole 120 and a welt 122 in which a thread lock formed by a needle thread 124 and locking thread 126 is set at a very shallow depth. The differences in thread lock depth represented by FIGS. 4 and 5 may be considered as the acceptable range in which a shuttle thread lock may be set and still retain commercial acceptance.

In FIG. 6 there is illustrated a stitch hole in an outsole 130 and a welt 132. In the stitch hole is a thread lock formed by a needle thread 134 and a locking thread 136, the lock being set at a medium depth in the work. A closer scrutiny of the arrangement of thread forming the thread lock in a shuttle lock seam with reference to FIGS. 6 through 8, by comparison with the subsequent analysis of a thread lock in a loop lock seam as depicted in FIGS. 12 through 15, will clarify the reasons for the greater permissible tolerance in shuttle lock setting depth and the greater holding power of the loop thread lock. Since a conventional shuttle lock stitch consists of two interlocked single bights, a cross section taken on a plane generally normal to the stitch hole and passing through the point of tangency or point of engagement of the two bights as shown in FIG. 7, represents the maximum thread cross section in each stitch hole. FIG. 8 on the other hand represents the minimum cross section in each stitch hole. The holding power of each stitch in a shuttle lock stitch seam is dependent almost entirely after the locking thread has been worn away on the surface of the sole, upon the wedging action of two additional thread diameters, the differences between maximum and minimum cross section, upon the wall of the stitch hole in the area of the thread lock only. Once the thread lock has been worn away as would occur before the sole is half worn to a stitch such as that shown in FIG. 5, the only holding power of the stitch derives from the bare adhesion of two thickness of thread to the wall of the stitch hole.

An important reason for the broad latitude in permissible thread lock depths is seen from FIG. 6 in which the length of enlargement in thread cross section is denoted by the reference character *b*. Since the locking thread is pulled into position by the action of the needle thread the dimension *b* regardless of the quality of a shuttle lock stitch or the depth to which the lock is set can never be greater than nor can it be substantially less than two thread diameters. Accordingly even in a shoe having a relatively thin outsole attached to a welt by means of a shuttle lock stitch seam, there is usually a sufficient range of acceptable thread depth and the problem of properly setting the stitch is not a serious one.

By contrast with the thread lock in a conventional lock stitch, the dimensions of a loop lock, together with defects in the form of the stitch increase the difficulty of setting a loop lock stitch in a commercially acceptable manner as will be seen from FIGS. 9 to 15 inclusive. Two layers of a work piece comprising an outsole 140 and a welt 142 are shown united in FIG. 9 by a loop lock stitch seam consisting of a needle thread 144 and a locking thread 146. The thread lock 144, 146 is shown in FIG. 9 set approximately at maximum depth and the

form of stitch is correct in that the locking thread bight indicated at 148 extends a minimum distance through the needle loop. The minimum extension of the locking thread bight through the needle loop is determined by the mode of stitch formation and of necessity often includes a greater length than is necessary for the needle thread engaging function.

In FIG. 10 there is shown a single stitch hole in a work piece comprising an outsole 150 and a welt 152. In the stitch hole is enclosed a loop lock stitch formed by a needle thread 154 and a locking thread 156. In the stitch of FIG. 10, however, the locking loop indicated at 158, although of generally tolerable length is objectionable because the bight 158 extends above the surface of the outsole. The stitch depicted in FIG. 10 is adequate in holding power but would be considered unacceptable from the point of view of appearance in a commercially manufactured shoe. Since this stitch is of correct form and set sufficiently deep for a shuttle lock stitch such as that of FIG. 5, it is seen that the range of thread lock depth for loop lock stitches is considerably narrowed.

In FIG. 11 there is illustrated a single loop lock stitch, part of a seam joining two layers of a work piece comprising an outsole 160 and a welt 162. The stitch is formed by a needle thread 164 and a locking thread 166 and the lock is set in the body of the outsole a medium depth which would be sufficient under normal conditions both from the point of view of appearance and that of durability. However, in the stitch illustrated in FIG. 11 the bight of locking thread indicated at 168 extends excessively through the needle loop and accordingly protrudes objectionably above the surface of the outsole. The failure of prior loop lock stitch sewing machines to control completely the length of locking loops to a uniform length and the nature of loop lock stitches which by their very nature have a much greater length of lock or thread enlargement than conventional shuttle thread lock stitches have contributed to the difficulties of setting loop lock stitches with the commercially required precision by means of conventional stitch setting devices.

In FIG. 12 a loop lock stitch, part of a seam, is shown in a single stitch hole formed in a work piece comprising an outsole 170 and a welt 172. The stitch of FIG. 12 consisting of a needle thread 174 and a locking thread 176 is accurately formed and set at a medium depth so as to be commercially acceptable. The bight of locking thread indicated at 178 is of sufficient length to provide holding power to the stitch and yet is short enough that it does not extend above the surface of the outsole.

It has already been pointed out, however, that the holding power of seams is largely dependent upon the difference between the maximum and minimum thread cross section in the individual stitch holes. From FIG. 13 it will be seen that in a plane normal to the length of the stitch hole and passing through the points of tangency where the needle thread engages the locking thread to form the lock there is a maximum cross section of six thread diameters. As in the case of a shuttle lock stitch the maximum thread diameter extends a distance *c* equal to two thread diameters along the length of the stitch hole. However, because the bight 178 is folded back about the needle thread 174 a distance *d* as shown in FIG. 12 the wedging effect of the thread lock is not limited to the distance *c* but also includes an intermediate thread cross section, shown in FIG. 12, equal to four thread diameters and of a length subject to vary widely in stitches formed on prior machines. As in the case of the conventional shuttle lock the minimum thread cross section consists of two thread diameters. The greater holding power of the loop lock stitch derives from a difference of four thread diameters rather than two between minimum and maximum cross section and from a somewhat lesser but still effective wedging action of the intermediate thread cross section extending a variable length in the stitch hole.

The greater holding power of the individual stitches of a loop lock seam over a shuttle loop stitch seam, dependent as it is upon a greater wedging action of the thread in the individual stitch holes, requires, all other factors being equal, the application of much greater tension to the needle thread to accomplish the setting of the stitch. When the greater stitch tensions required for loop lock stitches are applied to substantial lengths of needle thread, a factor of erratic thread elongation contributes to the irregularity in the depth to which successive thread locks are set.

In summary of the comparison of loop lock stitch seams and shuttle lock stitch seams it is seen that the loop lock stitch seam under comparable conditions has a substantially greater holding power. However, for a given thickness of work the range of depth to which the thread lock of a loop lock stitch may be set is considerably smaller than that available for the setting of a conventional shuttle lock stitch even under conditions of correct loop lock stitch form. When a loop lock stitch is defective because of the presence of a longer than necessary locking loop, for example, the already restricted range of lock setting depth is further diminished. These problems are further complicated by the fact that the setting of a loop lock stitch in the body of the work requires the application of substantially greater tension to the needle thread. This greater tension, when applied to substantial lengths of thread, tends, by erratic elongation of the thread, to introduce further irregularities in stitch setting depth.

In prior loop lock stitch sewing machines the foregoing factors contributing to stitch irregularity have not been fully appreciated and consequently these machines have not been entirely successful, particularly when operating upon relatively thin soled shoes, for example. In these prior machines the dual functions of contracting the needle loop and setting the stitch in the body of the work have been accomplished by a takeup of the same general type as is employed in shuttle lock stitch machines. As a result the greatest stitch setting force is applied in some of these machines to as much as 20" of thread which is stressed repeatedly during the formation of the seam and yields in an unpredictable manner thereby producing irregularities in thread lock depth.

By contrast in the present machine the maximum stress of stitch setting is applied to a relatively short length of thread on the order of 2 or 3" and the stitch setting tension is applied to the needle thread by the gripper 102 at a time when that thread is already under tension at a lower but predictable level. This is because the takeup 100 in the present machine is employed during the latter part of the sewing cycle following the introduction of the locking loop within the needle loop, for the sole purpose of contracting the needle loop only to that point where the locking loop is firmly gripped by the needle loop at the inlet to the stitch hole. Thereafter the stitch setting function is accomplished entirely by the gripper 102 which applies the maximum tension to a short length of thread thereby minimizing the effect of thread elongation under tension.

The stitch setting gripper 102 includes a generally L-shaped inner jaw 184 (FIGS. 24, 25, 27 and 28) pivoted at the forward end of a short link 186, the rearward end of which is pivotally supported on a block 188 fixedly mounted on the frame 16. The inner jaw 184 is perforated to receive an intermediate pivot 190 upon which is also supported a lever 192 serving to connect the gripper 102 with its actuating mechanism. At its upper end the lever 192 pivotally supports a jaw block 194 corrugated to the complement the thread engaging surface of the inner jaw 184. Because of its pivotal mounting, the block 194 along its entire length engages the needle thread 90 when the gripper 102 is closed.

To provide a regulated force under which the jaws

of the gripper 102 engage the thread, the inner jaw 184 is formed with a horizontal rearwardly extending arm 196 pivoted at 198 to a generally vertical stem 200. At its lower end the stem 200 is formed with an externally threaded hollow skirt 202 disposed within a sleeve 204, pivoted about an eccentric stud 206 adjustably fixed upon a bracket 208 secured to the frame 16. The pivot 198 is biased upwardly by a spring 210 inside the skirt 202 so as to be compressed between the skirt and the stud 206. The sleeve 204 is slotted at 214 to allow the assembly of the stem 200 and the sleeve to move downwardly after the jaws of the gripper have engaged the thread during the stitch setting motion. Further downward movement of the sleeve 204 after the stitch is set releases the needle thread at the end of a seam as will be explained. The distance from the pivot 198 to the stud 206 and the upward pressure of the spring 210 may be adjusted for different size needle thread by advancing or withdrawing the skirt 202 in the thread of the sleeve 204. The spring pressure under which the pivot 198 yields is determined by the orientation of the eccentric of the stud 206 which is locked in place by a check nut 216.

The actuation of the gripper 102 is accomplished through an operating lever comprising a forwardly extending arm 218 secured to a short shaft 220 rotatably supported in the frame. The arm 218 is pivotally connected at 222 to the lever 192 and the actuating lever also includes a generally rearwardly extending arcuately slotted arm 224 fixed upon the shaft 220.

Motion is imparted to the actuating lever through connections including a generally vertical connecting rod 226 which receives a regular cam-derived reciprocation during each sewing cycle. The extent of stitch setting motion is regulated by varying the point of connection between the rod 226 and the arm 224 the connection being a movable pivot 228 adjustable in the slot of the lever 224 to provide a short stitch setter motion when the pivot is most remote from the axis of the shaft 220 and a longer stitch setter motion when the pivot 228 is closer to the axis of the shaft 220.

For imparting the necessary reciprocation to the rod 226 there is provided on the auxiliary sewing shaft 14 a pair of conjugate cams 230 and 232. The main actuating cam 230 is engaged at its periphery by a follower roll 234, rotatable upon a main lever 236 pivoted upon a shaft 238. A pair of brackets 240 are fixed upon the frame 16 in spaced relationship to support the shaft 238 at its ends. The lever 236 has a downwardly extending generally L-shaped arm pivotally connected to the rod 226 at 241 and an auxiliary lever 242 is fulcrumed on the shaft 238 and yieldingly coupled to the lever 236. Carried on the distal end of the auxiliary lever 242 is a follower roll 244 engaging the periphery of the cam 232. The brackets 240 serve to restrain the levers 236 and 242 against movement in the direction of the axis of the shaft 238. The yielding coupling between the auxiliary lever 242 and the main lever 236 consists of a relatively slender finger 246 formed integral with the auxiliary lever and extending generally in parallel relation with that part of the main lever upon which the follower roll 234 is carried. The lever 236 carries at its upper extremity a set screw 248 which may be adjusted and locked by means of a check nut 250 to vary the force under which the follower rolls 234 and 244 are urged toward one another. By means of this yielding connection it is possible to compensate for minor variations from the theoretically correct contour of the cams 230, 232 to provide an essentially positive motion to the stitch setting gripper 102.

Two separate functions are performed by two distinct modes of operation of the gripper 102 during each sewing cycle. During the stitch setting motion the jaws of the gripper 102 are actuated first to grip the needle thread 90 firmly and then to continue in motion to set the stitch

in the body of the work piece. The range of motion for stitch setting is depicted in FIG. 25 where the broken line showing illustrates the inactive position of the gripper and the illustration in full lines represents the end of the stitch setting motion. The second function of the gripper 102, that of controlling the needle thread 90 during the threading of the needle by the looper 86, is accomplished by imparting to the jaws only a sufficient motion to cause them to grip the thread without moving it. These two functions of the gripper 102 will again be considered in their necessary time relationship in the sewing cycle in connection with the timing chart of the machine.

So that the work piece may be quickly removed from the machine without being held back by the needle thread at the end of the seam, it is necessary that after the setting of the last stitch the jaws of the stitch setting gripper 102 be opened and mechanism has accordingly been provided in the present machine to serve this purpose. In order fully to set the last stitch the cams 230 and 232 are designed so that upon stopping the machine the jaws of the gripper are at their lowest positions as indicated in solid lines in FIG. 25. Accordingly, the mechanism for opening the gripper jaws is actuated during the last few degrees of sewing shaft rotation by connections with the stopping mechanism of the machine operating independently of the cams 230 and 232.

For releasing the needle thread upon stopping of the machine the connections with the driving and stopping mechanism act upon the sleeve 204 which for this purpose is formed with an integral flange 256. Pivoted on the bracket 208 to 258 is a bell crank having a generally horizontal forked arm 260 which embraces the sleeve 204 and is in a position to engage the flange 256 to depress the sleeve when the bell crank is operated in a clockwise direction, as seen in FIG. 24. Before the end of a seam is reached the arm 260 is maintained out of engagement with the flange 256 by a spring 262 compressed between an ear 264 of the bracket 208 and a finger 266 which is an integral part of the bell crank. During the last stitch of the seam, a rod 268 having a forward end 270 of reduced diameter passing through a slot in a vertical arm 272 of the bell crank is pressed forwardly to rock the arm 260 into engagement with flange 256 on the sleeve 204 which is thereby depressed to cause the gripper 102 to release the needle thread.

At the time of stopping the machine the various instrumentalities which engage the needle thread along its entire path from the needle thread supply to the work support are released so that there is no strain upon the thread and it can accordingly be gripped with ease at the work support 8. For gripping the thread there is provided at the work support a nipper jaw 278 seen in FIGS. 2 and 27. The nipper jaw 278 is operated upon stopping the machine by connections similar to those disclosed in my above identified prior application, the connection being actuated by a solenoid 280 mounted below the level of the work support on the frame of the machine.

During regular sewing operations the quantity of thread drawn from the supply and made available to the needle for each stitch is determined by the movement of a pull-off 282 (FIGS. 25, 27 and 29) to which is imparted a regular motion during each sewing cycle. The pull-off 282 receives its motion from a cam on the main cam shaft 12 and the amount of thread measured for each stitch is determined by the position of a thread measuring arm 284 which is connected to the presser foot and hence is dependent for its position upon the thickness upon the work. The pull-off 282 and thread measuring arm 284 operate between a pair of thread lock consisting of an upper or front lock and a lower or rear lock. As in the machine of my prior application the locks, see also FIGS. 25 and 29, are opened and closed during each sewing cycle through the oscillation of a lever 286 pivoted

on the frame and carrying at its upper end a thread lock shoe 288 which is the movable part of the front lock. At its lower end the lever 286 carries a similar shoe 290 which is the movable part of the rear lock. As in the machine of the Knott application, the thread lock lever 286 is formed with a short gear sector in engagement with a driving sector 292 fixedly supported upon a shaft 294 which is oscillated in the frame to close one or the other of the locks through the movement of a horizontal rod 296. In addition to the normal opening and closing motions which the locks receive during the formation of a seam there is a provision for opening both locks at the end of the seam. For this purpose there is secured on the shaft 294 an upstanding arm 298 (FIG. 29) engageable by a horizontal rod 300 slidable in a bearing fixed to the machine frame. In stopping the machine the rod 300 is pressed forward to move the lever 286 to a mid-position to cause both locks to be opened so that the needle thread may be free along its entire path from the outlet of the wax pot indicated generally at 302 (FIG. 2) to the nipper jaw 278.

It has already been seen that during the stopping of the machine the stitch setting gripper 102 and both thread locks are opened. It has also been pointed out that the needle thread 90 in the present machine is free of devices which in prior machines apply a constant frictional drag along that part of the needle thread between the wax pot and the work piece and thereby interfere with the free flow of the thread. Whenever during the sewing cycle in present machine, a point along the thread must be temporarily arrested for control purposes, the thread is gripped firmly between jaws only as long as is necessary and thereafter is completely released.

The wax pot 302 does impose a certain drag upon the thread by virtue of a stripper 304 installed at the exit point for removing from the thread excess quantities of coating material. In order to permit setting of the final stitch of each seam in the present machine and at the same time to facilitate the holding of the needle thread by the nipper jaw 278, there is provided a solenoid operated auxiliary thread measuring device including a solenoid 306 (FIGS. 1, 2 and 27) energized before the machine is brought to rest to withdraw from the supply and through the wax pot a quantity of needle thread which is released when the machine is stopped to relieve tension in the active needle thread, that part extending between the stripper 304 and the nipper jaw 278. The solenoid 306 surrounds an armature 308 having a pivotal connection at 310 with an auxiliary pull-off 312. Supported on the upper surface of the wax pot is an L-shaped bracket 314, upon which is fixed a C-shaped member 316 having arms perforated at 318 and 320 above and below the auxiliary pull-off 312. Extending laterally from the bracket 314 is an anchor plate 322 to which is attached one end of a spring 324 the other end of which is connected to the auxiliary pull-off 312, and serves to withdraw the armature 308 from solenoid 306 when the latter is deenergized. In the withdrawn position of the armature 308 an eye 326 in the auxiliary pull-off 312 is in alignment with the perforations 318 and 320 of the member 316. Consequently when the jaw 290 of the rear thread lock clamps the thread and the solenoid 306 is energized to cause the eye 326 to move out of alignment with the perforations 318, 320, a quantity of thread is drawn through the wax pot to be made available when the locks and the gripper 102 are open for completely relieving the tension in the active needle thread.

As in the case of prior loop lock stitch shoe outsole sewing machines the present one is controlled for starting and stopping by means of a treadle 328 (FIG. 1) pivoted at its rear end on the machine frame 16 and connected at an intermediate point along its length to a vertical link rod 330. As in prior machines the treadle 328 controls the engagement and disengagement of a pair of clutches on the main sewing shaft 12. For driving the main driving

shaft at high speed a clutch lever 332 is operatively connected to the treadle 328 and is effective for pressing into engagement a driving clutch on the left end of the sewing shaft 12.

In addition to controlling the rotation of the sewing shafts the treadle is also operatively connected to a pawl lever 334 (FIGS. 16 and 18) which as in the machine of my prior application arrests the rotation of the sewing shaft in a predetermined position. Connections to the pawl lever 334 also press the rods 268 and 300 forward during the stopping of the machine for releasing the needle thread 90 from the gripper 102 and from the thread locks respectively.

The upper end of the link rod 330 (FIGS. 2 and 16) is pivotally connected to the forward end of a generally horizontal arm 336 the rearward end of which is pivoted on the machine frame. Also pivoted to the arm 336 is another link rod 340 connected to the clutch lever 332 and to mechanism for shifting the pawl lever 334 into and out of machine stopping position. The connection between the rod 340 and the clutch lever 332 is by means of a pair of collars 342 secured to the rod above and below a forked portion of the lever which embraces the rod. At its upper end the rod 340 is pivotally connected to a cam arm 344 so that depressing the treadle 328 causes the cam arm to move in a counterclockwise direction as seen in FIG. 17 and to engage a roll 346 on the rearward end of a lever 348. Movement of the pawl lever 334 into and out of the path of a stopping cam 350 (FIG. 18) on the main cam shaft 12 is controlled by an offset forward arm of the lever 348. For this purpose the pawl lever 334 is pivoted on the hub of a lever 352 and is biased by a spring 354 so that its upper end tends to move into the plane of the cam 350. While the machine is in operation the forward end of the lever 348 engages a set screw 356 on the pawl lever 334 to rock the pawl lever out of the path of the stopping cam 350. When the treadle is released at the end of a seam the lever 348, which is also part of the mechanism for engaging a low speed clutch to act as a brake upon the sewing shaft, is disengaged from the pawl lever 334 which under the influence of the spring 354 is rocked into the plane of the cam 350, to accomplish, during the last revolution of the shaft 12, a number of auxiliary functions that must be performed in stopping and finally to bring the sewing shaft to rest with an integral abutment 358 of the cam 350 in engagement with the upper surface of the pawl lever.

Movement of the pawl lever 334 outwardly from the axis of the sewing shaft 12 before stoppage of the machine is imparted to the lever 352 which is connected by means of a short link 360 to a lever 362 pivotally supported at the rear of the frame 16. The lever 362 is formed with a curved lower arm to the distal end of which the rods 268 and 300 are pivoted. The connections already described which are somewhat similar to those of my co-pending application, are effective for rocking the lever 362 in a clockwise direction as seen in FIG. 18 just before the machine comes to rest so that both the rods 268 and 300 are pressed forward to cause the opening of the gripper 102 and of the thread locks respectively.

As in the machine of my prior application, there are in the present machine switches which are closed near the end of the final sewing cycle to energize the solenoids 306 and 280 for measuring a quantity of needle thread and for gripping the free end of the needle thread when it is severed by an electrical resistance element 364 shown in FIG. 21. The resistance element 364 is of the same construction and mounting as the element 94 of my co-pending application, and accordingly is not to be described further in this application. As seen in FIGS. 16, 18 and 19 there is provided at the rear of the machine a pair of switches indicated at 366, 368 incorporated in the circuits of the solenoids 306 and 280 respectively. The switch 366 which is of the normally open type is closed momentarily by the engagement with its actuating button 370 of

an arm 372 secured to a horizontal rockshaft 374 journaled in the machine frame in generally parallel relation with the shaft 12. Wrapped about the shaft 374 is a torsion spring 376 which urges the shaft in a counterclockwise direction as seen in FIGS. 18 and 19 so as to maintain the arm 372 out of engagement with the button 370. For causing the arm 372 to engage the button 370 at the end of a seam, there is fixed to the rockshaft 374 an arm 378 which is engaged by the upper end of the lever 362 as the pawl lever 334 is pressed outwardly from the axis of the shaft 12 just before the stopping of the machine. The movement of the pawl lever 334 is translated into a rocking of the shaft 374 causing the arm 372 to engage the button 370 and thereafter to release the button as the lever 334 moves again closer to the axis of the shaft 12 just before engaging the abutment 358.

The switch 368 is actuated at the end of a seam and at the beginning of the succeeding seam, in the same manner as the switch 350 in my copending application although a slight change has been made in the actuation of the switch and in the operating mechanism effective at the start of new seam. The switch 368 has an actuating button 382 which is engaged by an arm 384 having a set screw 386 in engagement with the arm 378 so as to be rocked in a clockwise direction as seen in FIGS. 18 and 19 by the movement of the pawl lever 334 but before the machine comes to rest. At the clockwise extreme of its motion the arm 384 which is rotatably mounted on the rockshaft 374 is retained in engagement with the button 382 by a latch 388 pivoted on the machine frame and biased into engagement with the arm 384 by a spring 390. Once having engaged the button 382 at the end of a seam the arm 384 remains in engagement until the latch 388 is disengaged by the action of an adjustable lobe 392 on an otherwise cylindrical cam 394 mounted on the main shaft 12. For releasing the latch 388 a follower roll 396 mounted on an arm 398 pivoted on the frame engages the periphery of the cam 394 and is connected by a link rod 400 to the latch 388. The switch 368 which is of the normally open type is accordingly closed just before the machine comes to rest and remains closed until the latch 388 is released after the needle is withdrawn from the work during the formation of the first stitch. When the latch 388 is released the arm 384 is free to rock in a counterclockwise direction as seen in FIGS. 18 and 19, and is pulled out of engagement with the button 382 by the spring 390. In addition to the switches 366 and 368 there is also at the rear of the machine a double pole, double throw switch indicated at 402 in FIG. 16 which is actuated by a set screw 404 in an extension of the arm 336.

Referring now to FIG. 26, the switch 402 performs the same function in the present machine as the switch 313 in the machine of my prior application. When a switch 406 on a power control panel shown in FIGS. 1 and 2 is moved to the "on" position an indicator lamp 408 on the panel is lit and bus bars 410 and 412 are energized with 117 volts of 60 cycle A.C. Once the bus bars 410, 412 have been energized a second switch 414 also on the power control panel must be closed so that devices for severing and gripping the needle thread may be energized by the automatically actuated switches already described. Similarly, a toggle switch 416 must be manually closed in order to render operative the auxiliary thread measuring device which operates at the end of each seam to relieve the tension upon the needle thread.

When the switches 406, 414 are closed and the machine is in operation the switch 402 is effective for connecting the primary winding of a transformer 418 in series across the line with a high resistance 420 to maintain the resistance element 364 in preheated condition. While the machine is in operation a solenoid 422 which controls contacts 424 is energized, and the contacts remain closed. When the switch 402 is actuated by the arm 336 to open the lower pair of contacts and to close

the lower pair of contacts as shown in FIG. 26, the solenoid 422 is de-energized and after an adjustable time delay the contacts 424 are opened. During the period between the closing of the lower contacts of the switch 402 and the opening of the contacts 424, the primary winding of the transformer 418 is connected in series with a low resistance 426 across the line to heat the resistance element 364 to thread severing temperature.

When the switches 406 and 414 are closed and the end of a seam is reached the arm 384 is effective for closing the switch 368 causing the solenoid 280 to be energized so that the nipper jaw 278 is brought into gripping engagement with the needle thread. The switch 368 remains closed since the latch 388 retains the arm 384 in switch-closing position until after the needle has been withdrawn from the work during the first sewing cycle of the next seam.

With the switches 406 and 416 closed the momentary closing of the switch 366 by the arm 372 as the machine is coming to rest during the final sewing cycle of a seam is effective for energizing the solenoid 306, for withdrawing from the thread supply and through the wax pot 302 a quantity of needle thread. The closing of the switch 366 is only temporary occurring while the rear lock of the machine is closed so that the auxiliary pull-off 312 measures a quantity of needle thread which is released as the solenoid 306 is de-energized before the machine is brought to rest.

It has already been shown that by the use of the stitch setting gripper 102 in the present machine more accurate stitch setting is achieved than has heretofore been considered possible in loop lock stitch outsole sewing machines. It has also been pointed out, however, that certain factors such as the long lock thread loop depicted in FIG. 11 tend in loop lock stitch sewing to limit the range of depths at which the thread lock may acceptably be set. In large measure the malformation of individual stitches is traceable to deflection of the needle in prior machines which during a part of a sewing cycle employ the needle unassisted for feeding the work piece as will now be explained in connection with FIGS. 30 to 38 inclusive.

A loop lock stitch seam being correctly inserted in a work piece comprising an outsole 430 and a welt 432 is schematically illustrated in FIGS. 30 to 32 inclusive. The thread manipulating instrumentalities, for purposes of these illustrations, consist of a curved hook needle 434, a locking thread detaining finger 436 spaced rearwardly along the line of the seam a distance Y from the plane of the needle and a loop spreader 438. In FIG. 30 the needle 434 is shown at its point of deepest penetration through the work and in the process of unassistedly advancing the work piece at the same time that it is receiving the needle thread in its barb. Since, under the conditions illustrated in FIG. 30, the needle 434 is entirely free of lateral forces, the needle, upon withdrawal from the work piece to the position shown in FIG. 31, remains in alignment with the stitch hole from which it is emerging. Accordingly when the needle loop is opened by the loop spreader 438 and a loop of locking thread 440 is formed about the point of the finger 436 the length of the locking loop is determined by the dimension Y, which may be adjusted at the beginning of the seam for the particular conditions of work thickness and material under which the seam is being inserted. For purposes of clarity it will be assumed that the sewing conditions in FIGS. 30 to 38 inclusive are such that the dimension Y remains constant.

One type of defective loop lock is shown in FIGS. 33 to 35 in which a seam is being inserted in a work piece comprising an outsole 440 and a welt 442. In these figures the thread handling devices include a curved hook needle 444, a locking thread detaining finger 446 positioned a distance Y along the line of the seam from the needle and a loop spreader 448. In FIG. 33 the needle

444 is shown at its lowest point unassistedly advancing the work. The needle 444 unlike the needle 434, however, in feeding the work piece is being subjected to a drag or rearward pull and is accordingly deflected rearwardly along the line of the seam. When the needle withdraws from the work piece as shown in FIG. 34 it therefore springs forwardly from the last-formed stitch hole and although the dimension Y remains constant the distance from the last needle hole to the point of the finger 446 indicated by the reference character N is shorter than the dimension Y. As a result not only is the distance between stitch holes in a seam so formed shorter than normal but the locking loop, as shown in the last completed stitch in FIGS. 33 and 34, extends an insufficient length through the loop of needle thread. Under extreme conditions the locking loop is so shortened by excessive rearward deflection of the needle that the needle loop slides off the locking loop during stitch setting and a stitch is completely missed.

A second form of defective loop lock stitch is shown in FIGS. 36 to 38 inclusive which illustrate a seam being inserted in a work piece comprising an outsole 450 and a welt 452. The instruments for handling the thread in these figures comprise a needle 454, a locking thread detaining finger 456 again spaced rearwardly along the line of the seam a distance Y from the needle plane and a loop spreader 458. The needle 454 is shown at its point of deepest penetration in FIG. 36 and unassistedly feeding the work piece which is being pressed forwardly so that the needle is accordingly deflected out of the needle plane, along the line of the seam. When the needle 454 is withdrawn from the work piece carrying a loop of needle thread as shown in FIG. 37 it springs rearwardly toward the finger 458. Under these circumstances the distance indicated by reference character P from the finger 458 to the last formed perforation is greater than the constant Y. Accordingly the locking loop of the stitch being formed as in the case of the last completely formed stitch illustrated in FIGS. 36 and 37, is defective in that it includes a locking loop projecting excessively through the needle loop. The elongated locking loop thus produced tends to protrude above the sole 450 and thereby to render the shoe commercially unacceptable. Under less severe circumstances when the distances P and Y are more closely commensurate the result of minor needle deflection is to reduce the effective range in which the thread lock may acceptably be set, as has already been explained in detail with reference to the single stitch illustrated in FIG. 11.

In the prior loop lock stitch outsole sewing machines in which the work piece is advanced during a part of each sewing cycle by the needle without assistance from another work feeding instrumentality, the uniform stitch lengths and correct stitch formation depicted in FIGS. 30 to 32 may be achieved but only by a thoroughly experienced operator exercising extreme care. Unassisted work feed by the needle during a part of each sewing cycle reduces machine control over the work piece and frequently results in work feeding error and accompanying defective stitches such as those illustrated in FIGS. 33 and 36. Although defective stitches resulting from work feed error are most likely when the machine is under the control of an inexperienced or careless operator, these defects frequently occur in operating upon shoe styles in which the outsole has an abruptly curving form or during transition from one type of shoe to a radically different type. In the same shoe it is possible, in prior machines, to encounter both the defects illustrated in FIGS. 33 and 36, the former defect being most probable in the most abruptly curved portions of the seam such as the toe and shank and the latter defect occurring most frequently in relatively straight portions of the seam.

In conventional lock stitch machines as opposed to loop lock stitch machines which are the subject of the present invention there is also the problem of needle

deflection when the work feed is accomplished during a part of the sewing cycle by the needle without assistance from another instrumentality. However, in conventional lock stitch machines needle deflection has little effect upon the placement of the thread in the individual stitch holes and the form of the stitch is such, as has already been explained, that much greater variations in stitch setting depths may be readily tolerated. Also, in conventional lock stitch machines, the variations in stitch length which result from needle deflection are considered acceptable in view of a conviction that a certain degree of feeding error is unavoidable and in any event does not affect the holding power of the seam.

In the present machine the movements of the needle 2, of the awl 4 and of the work feeding clamp comprising the work support 8 and the presser foot 10 are co-ordinated in a novel time sequence to obtain the benefits of continuous work feed and of work squeezing engagement and an inward component of motion by the work feeding clamp, which characterize the machine of the above identified Knott application. At the same time, it will be seen that the relative timing of the work piercing and feeding instrumentalities in the present machine results in fuller control of the work piece by the machine during the formation of each stitch and in the substantial elimination of needle deflection and of the attendant malformation of stitches.

As seen in FIG. 39 which is the timing chart of the machine the needle 2 during the first 60° of sewing shaft rotation is either close to or at the uppermost limit of its movement and completely out of engagement with the work piece. At the 60° point in the sewing cycle the needle starts to descend toward the work piece, the penetration of a work piece of normal thickness occurring at approximately the 95° position of the sewing shafts. Before the needle enters the work piece, the awl 4 having commenced its approach to the work piece at the end of the prior sewing cycle, projects above the top surface of the work support 8 at approximately the 6° point of the sewing cycle and continues to penetrate through the work piece at an essentially constant rate until the 20° point is reached and then the penetration of the awl is decelerated, the point of maximum penetration being reached at the 35° point in the sewing cycle. The awl dwells in its position of deepest penetration through the work until the 72° position of the sewing shaft is reached and then begins to withdraw from the work piece, the withdrawal being completed as the point of the awl descends below the top of the work support at approximately 100° of the sewing cycle. The needle 2 enters the perforation formed by the awl as the awl is being withdrawn and reaches its point of deepest penetration at the 135° point in the sewing cycle, the awl, at this point, being in its fully withdrawn position and continuing in this position until the needle has started to withdraw from the work piece. During a dwell in the needle movement at its point of deepest penetration from 135° to 144° and as the needle begins to withdraw, it is threaded by the operation of the looper 36 as shown by the graph entitled "Looper Motion" in the time chart. The looper motion as related to the position of the needle 2, is similar to that of prior machines, the operation of laying needle thread in the barb of the needle being completed as the looper moves to the right and rear of the needle commencing at 135° in the sewing cycle. Before moving to thread the needle, the looper places the needle thread behind the thread hook 6 which thereafter moves rearwardly in generally conventional manner to store thread preliminary to the withdrawal of the needle, pauses while the needle is being threaded, and moves forwardly to supply thread as the needle is being withdrawn to prevent reaving of the thread in the barb of the needle.

During the first 30° of sewing shaft rotation in each sewing cycle, work feed is accomplished by the clamp comprising the work support 8 and the presser foot 10.

The awl after rising above the upper surface of the work support cooperates as it is penetrating the work piece in advancing the work piece at the same rate as the work feeding clamp. Between the 30° and 80° points in sewing cycle the awl continues unassisted to advance the work piece as the presser foot is lifted starting at the 30° point and the work feeding clamp 8, 10 is backfed, the backfeeding movement being completed at the 80° point in the sewing cycle, at which time the presser foot starts to engage the work and the work advancing function is thereafter transferred to the work feeding clamp.

In the present machine the 80° position of the sewing shafts is the "focus" position corresponding to the 145° position of the sewing shaft in the machine of the above-identified Knott application. The importance of a "focus" position for alignment of the work feeding instrumentalities is explained in detail in the Knott application and represents a further benefit of prior machines which has been retained in the present construction.

At the 85° position of the sewing shaft the presser foot starts to descend into engagement with the work piece, the presser foot lock, not shown, being unlocked for the purpose before the start of presser foot descent and again locked at the 95° position of the sewing shaft before the presser foot motion is terminated at the 105° position of the sewing shaft. During the rotation of the sewing shafts from the 95° to the 105° position, the presser foot applies a squeeze to the work piece, but the work advancing function is under the control of the work feeding clamp starting at the 95° position.

Whereas in the Knott machine the needle feeds the work unassisted during part of the sewing cycle and may be deflected, the needle 2 of the present machine is completely out of engagement with the work piece as the work feeding clamp is being backfed. In the Knott machine in the event of needle deflection the re-engagement of the work feeding clamp after it has been backfed prevents the correction of needle deflection. In the present machine on the other hand, there is no possibility of needle deflection since the work feeding clamp is in full engagement with the work piece before the needle penetrates the work piece.

In order to control the needle thread to prevent stranding in prior machines it is necessary to engage the thread frictionally between the takeup and the looper so as to control that portion of the needle thread being operated upon by the looper. Stranding is the insertion of but a part of the thread in the barb of the needle resulting in a defective stitch and frequent thread breakage. In the present machine a closing motion is imparted to the gripper 102 beginning at the 120° position of the sewing shaft so that the needle thread is firmly gripped below the looper while the looper lays the needle thread in the barb of the needle. This novel arrangement, together with the elimination of frictional thread controlling devices along the entire path of needle thread beyond the wax pot in the present machine permits the carrying of coatings by the thread without being removed by a frictional control device. In the present machine the needle thread either flows in complete freedom from frictional engagement or the thread is positively stopped at a control point by the gripper 102 or the lock shoes 288 and 290.

From its dwell terminating at the 144° position in the sewing cycle the needle begins its withdrawal from the work piece and emerges from a work piece of normal thickness at the 184° position of the sewing shaft. Movement of the needle away from the work piece terminates at the 224° position of the sewing shaft. The loop spreader 92 in the present machine operates in approximately the same manner as that of the Knott machine moving forwardly beginning at the 198° position of the sewing shaft to spread the needle loop which is fully opened at the 233° position of the sewing shaft. Starting at the 205° position the locking thread carrying fin-

ger 88 moves toward and into the spread needle loop completing its penetration at the 250° position of the shaft. The movement of the thread carrying finger is approximately the same as that of the corresponding element of the Knott machine as is also the movement of the detaining finger 96 which descends into engagement with the work piece to trap the locking thread as the finger 88 having overtraveled beyond the detaining finger begins its withdrawal from the needle loop.

In the present machine the engagement of the work piece by the work feeding clamp at the 95° position of the sewing shafts and the continuation of the engagement for the remainder of the sewing cycle affords not only more even control of the work piece but also greater accuracy of needle thread measurement than has heretofore been attainable in loop lock stitch outsole shoe sewing machines provided with continuous work advancing devices. Control of the needle thread in a loop lock stitch sewing machine involves the cooperation of the looper, the thread hook, the loop spreader, the takeup, the thread locks, the pulloff and the thread measuring arm. In the present machine the takeup 100 from the start of the sewing cycle until the 230° position of the sewing shafts is reached, is in motion toward the work support with the result that the path of the needle thread is continuously being shortened and thread is thereby being made available to satisfy the requirements of other instrumentalities. For the first 44° of the sewing cycle the upper thread lock 288 is fully opened and a portion 20 of the thread yielded by the takeup is required for the motion of the looper 86 to place the needle thread in engagement with the thread hook 6. Thereafter the thread hook in moving to the rear takes up an additional quantity of the thread given up by the takeup before 25 the needle is threaded by the action of the looper. Between the 44° and the 100° positions of the sewing shafts the lever 286 is shifted to close the upper lock 288 and open the lower lock 290. In preparation for the measurement of needle thread for formation of the succeeding stitch, the thread locks remain in this condition until the 230° position of the sewing shaft is reached. For accurate thread measurement it is important that during the portion of the sewing cycle between the 100° and 230° positions of the sewing shafts, the thread measuring period, the work piece be under firm control and the presser foot 10 which not only feeds the work but also gages its thickness be immune from uncontrolled changes in position.

The graph entitled, "Machine Thread Measuring," represents the operation during the formation of one stitch, of the pulloff 282 in cooperation with the thread measuring arm 284 in withdrawing the needle thread from the supply and into the machine for the next stitch of the seam. The pulloff 282 has a regular thread storing motion starting at the 135° position of the sewing shaft and terminating at the 230° position. For the thickest work for which the machine is suited the entire thread storing motion of the pulloff is effective because of the orientation with respect to the pulloff of the thread measuring arm 284. For thin work on the other hand the thread measuring arm 284 which is connected to the presser foot 10 to determine its orientation relative to the pulloff stroke renders ineffective the thread storing motion of the pulloff except for the 35° of sewing shaft rotation between the 195° and 230° positions. Accordingly a minimum quantity of needle thread is measured during 35° of sewing shaft rotation whereas the maximum quantity required for the thickest work is measured during 95° of sewing shaft rotation. Since the work piece is fully under the control of the work feeding clamp at the 95° position of the sewing shaft and the presser foot motion is terminated at the 100° position at which time the upper lock is closed and the lower lock is open there is no possibility that the thread

measuring function will be disturbed by erratic presser foot motion during the entire thread measuring period.

At the 230° position of the sewing shaft the thread measuring period is completed, the takeup 100 and the pulloff 282 come to rest, dwell for 10° of sewing shaft rotation and then reverse their direction of motion. At the same time the thread lock lever 286 starts to move to close the lower lock 290 and to open the upper lock 288. The reversal of the takeup motion starting at the 240° point in the sewing cycle is effective for pulling ahead of the front lock 288 the thread previously stored by the pulloff 282 which continues to yield thread until the 280° point is reached in the sewing cycle, and thereafter dwells in a stationary position until the start of the next thread measuring period. The action of the takeup 100 which continues to increase the path of the needle thread until the 320° position of the sewing shaft is reached also contracts the needle loop. Preparatory to being contracted by the action of the takeup, the needle loop has been opened to maximum extent by the loop spreader 92 for the introduction of locking thread by the finger 88. By the time that the 280° position of the sewing shaft is reached the detaining finger 96 is in contact with the work piece trapping a loop of locking thread, the locking thread carrying finger 88 is retracting from its needle loop penetrating position, the loop spreader 92 has moved completely rearwardly and no longer controls the needle loop and the castoff 98 has engaged the needle loop released by the spreader 92 for disengaging the needle thread from the barb of the needle. The thread withdrawing motion of the takeup 100 is uninterrupted through the 280° position of the sewing shafts and ends at the 320° position. At the end of the thread retracting motion of the takeup the needle loop is almost fully contracted to the point where the locking loop having been formed about the detaining finger 96 is at the inlet to the stitch hole and ready to be pulled into the body of the work by further tension applied to the needle thread.

For the stitch setting function the gripper 102 is closed starting at the 300° position of the sewing shaft and is fully closed at the 320° position at the time that the thread retracting motion of the takeup is completed. Thereafter the rod 226 continues to move upwardly and the gripper 102 having closed firmly upon the needle thread pulls upon the needle thread to set the stitch in the body of the work piece, the stitch setting motion of the gripper continuing until the 360° position of the sewing shafts. Cooperating with the takeup and the gripper 102 is the detaining finger 96 which begins to rise from its locking thread detaining position at the 305° position of the sewing shaft and since the detaining finger has penetrated somewhat into the body of the work piece, it retains control over the locking loop until the start of the stitch setting motion of the gripper 102.

Having thus described my invention what I claim as new and desire to secure by Letters Patent of the United States is:

1. A machine for inserting a loop lock stitch seam in a leather work piece comprising stitch forming devices including a curved hook needle adapted to penetrate the work and to withdraw carrying loops of needle thread, means including a takeup for yielding thread to the needle and for retracting thread to contract the needle loop and to set the stitch, a work feeding clamp including a presser foot and a work support, and means for imparting to the clamp a continuous work feeding movement commencing in each stitch forming cycle before the needle is threaded and terminating after the stitch has been set.

2. The machine of claim 1 further comprising a work piercing awl and means for imparting to the awl a work feeding movement while the clamp is being backfed prior to its next work feeding movement.

3. The machine of claim 1 further comprising a thread

gripper and actuating means for imparting a stitch setting motion to the gripper after the takeup has contracted the needle loop but before the work feeding movement of the clamp is terminated.

5. The machine of claim 3 in which the actuating means comprises a cam and a single set of connections for closing the gripper upon the needle thread and for thereafter imparting to the gripper a stitch setting motion.

10. A machine for inserting a loop lock stitch seam in a leather work piece comprising a work piercing awl, stitch forming devices including a curved hook needle adapted to penetrate the work piece and to withdraw carrying loops of needle thread, means for introducing loops of locking thread into the spread loops of needle thread, means including a takeup for yielding thread to the needle as it is being withdrawn from the work and the loop is being further opened, and for retracting thread to contract the needle loop and to set the stitch, a work feeding clamp including a presser foot and a work support, and means for imparting to the clamp a continuous work feeding movement commencing in each stitch forming cycle as the needle first enters the work and terminating after the stitch has been set.

25. The machine of claim 5 further comprising a thread gripper and actuating means for imparting to the gripper a stitch setting motion during the work feeding movement of the clamp.

30. The machine of claim 6 further comprising means for opening the gripper just before the machine is brought to a stop at the end of the seam.

35. The machine of claim 6 further comprising thread measuring means including a pulloff effective during each sewing cycle for measuring thread necessary for formation of the next stitch, an auxiliary pulloff and means for actuating the auxiliary pulloff to withdraw thread from the supply before the machine is brought to rest.

40. The machine of claim 6 further comprising stitch forming devices including a curved hook needle adapted to penetrate the work and to withdraw carrying loops of needle thread, takeup means for yielding thread to the needle, for retracting thread and for contracting the needle loop to bring the locking loop to the inlet of the stitch hole, gripper means, actuating means for the gripper means for applying a stitch setting tension to the needle thread after the contraction of the needle loop has brought the locking loops to the inlet of the stitch hole, and means separate from the gripper actuating means for opening the gripper automatically at the end of a seam thereby permitting ready withdrawal of the work piece.

45. The machine of claim 6 further comprising a curved hook needle adapted to penetrate the work and to withdraw carrying loops of needle thread, takeup means for yielding thread to the needle and thereafter contracting the needle loop to a point where the locking loop is brought to the inlet of the stitch hole, gripper means, and actuating means for first closing the gripper means upon the needle thread during the operation of the needle threading means and for then imparting both a closing and stitch setting motion to the gripper means later in the sewing cycle.

55. The machine of claim 10 further comprising means for opening the gripper means before the machine is brought to rest at the end of a seam.

60. The machine of claim 10 further comprising a curved hook needle adapted to penetrate the work and to withdraw carrying loops of needle thread, takeup means for yielding thread to the needle and thereafter contracting the needle loop to a point where the locking loop is brought to the inlet of the stitch hole, gripper means, and actuating means for first closing the gripper means upon the needle thread during the operation of the needle threading means and for then imparting both a closing and stitch setting motion to the gripper means later in the sewing cycle.

65. The machine of claim 10 further comprising a curved hook needle adapted to penetrate the work and to withdraw carrying loops of needle thread, takeup means for yielding thread to the needle and thereafter contracting the needle loop to a point where the locking loop is brought to the inlet of the stitch hole, gripper means, and actuating means for first closing the gripper means upon the needle thread during the operation of the needle threading means and for then imparting both a closing and stitch setting motion to the gripper means later in the sewing cycle.

70. The machine of claim 10 further comprising a curved hook needle adapted to penetrate the work and to withdraw carrying loops of needle thread, takeup means for yielding thread to the needle and thereafter contracting the needle loop to a point where the locking loop is brought to the inlet of the stitch hole, gripper means, and actuating means for first closing the gripper means upon the needle thread during the operation of the needle threading means and for then imparting both a closing and stitch setting motion to the gripper means later in the sewing cycle.

75. The machine of claim 10 further comprising a curved hook needle adapted to penetrate the work and to withdraw carrying loops of needle thread, takeup means for yielding thread to the needle and thereafter contracting the needle loop to a point where the locking loop is brought to the inlet of the stitch hole, gripper means, and actuating means for first closing the gripper means upon the needle thread during the operation of the needle threading means and for then imparting both a closing and stitch setting motion to the gripper means later in the sewing cycle.

75. The machine of claim 1 further comprising a thread

actuating means comprising a single mechanism for closing the gripper near the end of each sewing cycle and for moving the gripper bodily for applying a stitch setting tension to the needle thread, and means for automatically opening both thread locks and the gripper means before the machine is brought to rest at the end of the seam.

13. The machine of claim 12 further comprising a pull-off operating between the thread locks for withdrawing needle thread from a thread supply for the formation of each stitch of a seam, an auxiliary pulloff means effective before reaching the end of a seam for withdrawing a quantity of thread from the supply and for making the thread available as the locks and gripper are opened at the end of the seam.

14. A machine for inserting a loop lock stitch seam in a work piece comprising a leather work support, stitch forming devices including a curved hook needle adapted to penetrate the work and to withdraw carrying loops of needle thread, thread controlling devices including a take-up, front and rear thread locks, and a pulloff for withdrawing thread from a supply for the formation of each stitch of a seam, means on the work support for severing the needle thread at the end of the seam and for gripping the leading end of the thread in the machine, auxiliary pull-off means for withdrawing thread from the supply and for making the withdrawn thread available to the thread controlling devices before the machine is brought to rest at the end of a seam, and means for opening the thread locks in stopping the machine whereby the thread furnished by the auxiliary pulloff serves to relieve tension on the thread gripping means at the work support.

15. The machine, according to claim 14, further comprising means for setting the stitches in the body of the work piece during each sewing cycle, and means for releasing the stitch setting means from engagement with the needle thread during the final sewing cycle of a seam before the machine is brought to rest.

16. A machine for inserting a seam into a thick, resistant work piece such as a shoe sole comprising work feeding and stitch forming devices including a curved hook needle, means for interlocking the needle thread with a locking thread, a front thread lock and a rear thread lock, thread measuring means acting upon the needle thread between the locks, takeup means for contracting needle loops to bring the interlocked portions of the threads into engagement with the surface of the work, and means for thereafter setting the interlocked portions within the body of the work including a thread gripper acting on a portion of the needle thread between the takeup means and the work and a single set of connections for closing the gripper and imparting to it a stitch setting motion.

17. A machine for inserting a seam into a thick, resistant work piece such as a shoe sole comprising work feeding and stitch forming means including a curved hook needle, means for interlocking the needle thread with a locking thread, a front thread lock and a rear thread lock, thread measuring means acting upon the needle thread between the locks, takeup means for contracting needle loops to bring the interlocked portions of the threads into engagement with the surface of the work, means for thereafter setting the interlocked portions of

each stitch within the body of the work including a thread gripper acting on a portion of the needle thread between the takeup means and the work, a single set of connections for closing the gripper and imparting to it a stitch setting motion, and means separate from the closing connections for opening the gripper upon stopping the machine at the end of a seam.

18. A sewing machine for inserting a seam in a leather work piece comprising a work support, work feeding and stitch forming devices including a hook needle, means applying frictional resistance to the needle thread, a front thread lock and a rear thread lock, thread measuring means including a pulloff operating on the needle thread between the locks, auxiliary pulloff means for pulling thread from the supply past the frictional resistance applying means as the machine is being brought to a stop at the end of a seam, thread cutting means mounted on the work support for severing the thread when the machine is stopped, a thread gripper at the work support for holding the leading end of the severed thread for the start of the new seam, means actuated during the stoppage of the machine to open the locks, and means for releasing the thread withdrawn by the auxiliary pulloff means to relieve tension on the gripped thread.

19. A shoe outsole sewing machine comprising work feeding and stitch forming devices including a curved hook needle adapted to penetrate the work and to withdraw carrying a loop of thread, takeup means for yielding thread to the needle and for retracting thread to contract the needle loop, a stitch setting gripper including a pair of pivotally connected jaws, a lever connected to one of the jaws, cam means for imparting a closing and stitch setting motion to the jaws of the gripper and connecting means including a rod interposed between the cam means and the lever.

20. A machine of claim 19 further comprising an adjustable connection between the rod and the lever to vary the gripper motion derived from a regular motion of the rod.

21. A machine for inserting a loop lock stitch seam in a leather work piece of variable thickness comprising stitch forming devices including a curved hook needle adapted to penetrate the work and to withdraw carrying loops of needle thread, a work piercing awl, means for imparting to the awl a continuous work advancing movement during a part of the sewing cycle, a work support, a presser foot, means for imparting to the work support and presser foot a back feeding movement while the work piece is being advanced by the awl and a continuous work advancing movement during the remainder of the sewing cycle, means including a pulloff and a thread measuring arm for measuring needle thread in accordance with work thickness, and means for actuating the pulloff only during that part of the sewing cycle while the work is being advanced by the work support and the presser foot.
